PLAYING BALL

Charles H. Hanshaw, Beloit, Wis.

Application May 20, 1936, Serial No. 88,736

2 Claims. (Cl. 273—58)

This invention relates to improvements in playing balls.

The object of the invention is to provide a resilient ball, preferably of rubber, which has a surface formation which when the ball is thrown against a rebound surface, as a side walk or the like, will introduce an element of uncertainty in the direction or angle of the rebound.

Children play numerous games with rubber balls and after a time many become very proficient in catching the balls on the rebound due to the regularity at which they are returned by a smooth rebound surface.

In playing with a ball embodying the present improvements more alertness in catching the ball is required, due to the fact that while the improved ball may be returned by the rebound surface at an angle equal to the angle at which it struck the surface, it is likely to rebound at an entirely different and unexpected angle and hence greater alertness on the part of the player and greater expertise in catching the ball are required and the player's interest in the particular game is prolonged.

In the accompanying drawing:

Figure 1 is an elevation of a ball embodying the present improvements.

Figure 2 is a top plan view of the ball illustrated in Figure 1.

Figure 3 is a sectional view taken on line 3—3 of Figure 1.

Figure 4 is an elevation of a modified form of the invention.

Figure 5 is a section taken on lines 5—5 of Figure 4.

In Figures 1 to 3 of the drawing, the ball proper is indicated by the numeral 10, and preferably is formed of any suitable rubber composition which gives the ball resiliency and satisfactory rebound characteristics for use in playing sidewalk or like games so popular with children, although it may, of course, be used in playing games where a bat is used.

The exterior surface of the ball is generally spherical but as shown in Figures 1 to 3, two annular intersecting bands 11 and 12 are provided on the exterior which preferably are disposed in diametrical planes at right angles one to the other. These bands, as illustrated, are curved or convex in cross section and preferably are molded integrally with the ball and of the same resilient material of which the ball is made.

The disposition of the bands 11 and 12 as described divides the exterior of the ball into four semi-spherical impact segments 13, each being of

such area that it solely may strike a rebound surface and cause the ball to rebound in the same manner as it would were the bands not present, that is, the angle of rebound will equal the angle of approach. However, if one of the bands 11 or 12 also strikes the rebound surface, the angle of rebound will be affected thereby and uncertainty in the direction of return of the ball is thereby introduced. It will be seen that any of the four impact segments or areas 13 may so strike the rebound surface that the ball will be returned at the expected angle and that in some instances the bands 11 or 12 may so strike the surface as to cause the ball to rebound as expected. However, should the ball be so thrown that a portion of one of the spherical areas 13 and also a portion of one of the bands impact the surface, the rebound will likely be at an unexpected angle.

The same will be true when a lateral portion of a band impacts the rebound surface. It will, therefore, be seen that upon repeatedly bouncing the ball against a smooth surface, even though the ball may strike the surface at the same angle at each throw, the angles of rebound are likely to be varied, depending upon which portions of the ball impact the surface.

Instead of providing the spherical surface of the ball 10 with the continuous annular protuberances or bands above described, semi-spherical impact bosses or button-like protuberances 14, as illustrated in Figures 4 and 5, may also be used to obtain similar results. These formations 14 preferably are formed integrally with the ball and of the same material. Six such members 14 are shown, distributed equi-distantly one from another upon the spherical surface which is thereby divided into segmental impact areas which will cause the ball to rebound at predictable or expected angles when any one of the same alone strikes the rebound surface. However, should any one of protuberances 14 also contact the surface, it will affect the angle at which the ball rebounds.

I am aware that balls with ornamental annular bands and other surface formations have heretofore been made. Such bands or protuberances, however, have been closely spaced and constitute the impact area of the ball. With the present improvements the protuberances, whether in the form of continuous bands as shown in Figures 1 to 3 or of bosses or button-like projections as illustrated in Figures 4 and 5, are so relatively spaced as to leave available the major portion of the relatively uniform spherical surface for im-

pact purposes which in cooperation with the protuberances render quite unpredictable the angle at which the ball will rebound.

While I have shown and described certain embodiments of my improvement for the purpose of illustration, I do not wish to be restricted specifically thereto except as so limited by the appended claims.

I claim:

1. A resilient ball having an exterior surface composed of semi-spherical impact areas and interposed protuberant impact bands encircling the exterior.

2. A resilient ball having an exterior surface composed of semi-spherical impact areas and interposed protuberant annular impact bands disposed in diametrical planes of the ball. 5

CHARLES H. HANSHAW.
